US0D1099459S

(12) **United States Design Patent** (10) **Patent No.:** **US D1,099,459 S**
(45) **Date of Patent:** **** Oct. 21, 2025**

(54) **LITTER RECEPTACLE**

(71) Applicant: **LANDSCAPE FORMS, INC.**,
Kalamazoo, MI (US)

(72) Inventors: **Daniel Lobitz**, New York, NY (US);
Thomas Day, New York, NY (US);
Kirt Martin, Ada, MI (US); **Brian Revoir**, Vicksburg, MI (US)

(73) Assignee: **LANDSCAPE FORMS, INC.**,
Kalamazoo, MI (US)

(**) Term: **15 Years**

(21) Appl. No.: **29/911,353**

(22) Filed: **Sep. 1, 2023**

(51) LOC (15) Cl. **09-09**

(52) U.S. Cl.
USPC **D34/1**

(57) **CLAIM**

The ornamental design for a litter receptacle, as shown and described.

DESCRIPTION

FIG. 1 is a front right perspective view from above of a litter receptacle according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof; and,

FIG. 9 is a front right perspective view of the litter receptacle without a lid.

The broken lines in the drawings illustrate portions of the litter receptacle and form no part of the claimed design.

1 Claim, 9 Drawing Sheets
